CLAIM

The ornamental design for a boombox, as shown and described.

DESCRIPTION

FIG. 1 is a perspective view of a boombox;
FIG. 2 is a front perspective view thereof, with the handle shown in an upright position;
FIG. 3 is a rear perspective view thereof, with the handle shown in an upright position;
FIG. 4 is a bottom view thereof;
FIG. 5 is a top view thereof;
FIG. 6 is a front view thereof;
FIG. 7 is a back view thereof;
FIG. 8 is a side view thereof; and,
FIG. 9 is a side view thereof.
The broken lines in the drawings depict boundaries of the claims and form no part thereof.
